Re. 18,556

UNITED STATES PATENT OFFICE

ARTHUR L. CORNWELL, OF WELLSVILLE, NEW YORK

WHEEL PULLER

Original No. 1,764,243, dated June 17, 1930, Serial No. 347,571, filed March 16, 1929. Application for reissue filed June 13, 1932. Serial No. 617,016.

This invention relates to devices for pulling gears or wheels from axles or shafts on which they are mounted, and while having other and more general fields of usefulness, is well adapted and designed for removing wheel hubs of automobiles from axles on which they are fitted. The particular embodiment of the invention herein illustrated is especially designed for wheel puller uses 10 on the current types of Ford cars and trucks, as will hereinafter more fully explained. A principal object of the invention is to provide a wheel puller of this type that is capable of being easily and quickly applied with the capability of engaging the hub flange or equivalent strongly and reliably at opposite sides thereof, exerting an evenly distributed pull at opposite sides of the hub with a gripping effect or clamping effect upon the hub that 20 increases automatically and correspondingly with the increase of pull. Further objects are to provide a simple, strong and reliable device that is instantly and easily adjusted to different sizes and designs of wheel hubs 25 within its range with an equally effective clamping and pulling action upon each of the different types and sizes of hubs for which it is designed.

Wheel pullers of the type of my invention 30 ordinarily comprise a body member with means for engaging the hub of the wheel to be pulled and a power screw threaded into the body member and engageable with the axle to force the wheel therefrom. It is well known that a considerable force is required to loosen these wheels from their 35 axles and this requirement not only demands much work and effort from the operator but also places a considerable strain on the puller. One improved feature of my invention is the provision of means by which much of this effort and strain is eliminated and the wheel pulled with greater ease and efficiency. This means is in the nature of a 40 hammerhead handle on the power screw and adapted to receive the blows of a hammer to cause rotation of the screw and jarring of the wheel in the pulling operation. The provision of such a means for simultaneously 45 vibrating the wheel and rotating the power

screw comprises one of the objects of my invention.

The foregoing and other objects and advantages of the invention will be better understood from the following detailed description taken in connection with the accompanying drawing and the distinctive features of novelty will be thereafter pointed out in the appended claims.

Referring to the drawing:

Fig. 1 is a view partly in elevation and partly in longitudinal section showing a preferred embodiment of the invention applied to the wheel hub of a current Ford truck;

Fig. 2 is an elevation at right angles to Fig. 1;

Fig. 3 is a fragmentary elevation showing the manner of engagement of the device with the hub of a current type of Ford car; and

Fig. 4 is a fragmentary section taken on line 4-4 of Fig. 1; and

Fig. 5 is a sectional detail illustrative of the pivoted latch structure.

10 indicates the body of the device which is of stout integral construction provided at an intermediate point with a bore 11, which provides a bearing for a stout pin 12. This pin has its ends engaged in the sides of a stout latch or stirrup member 13, which is thus pivoted to the body 10. This latch or stirrup is of a dimension so that its sides will clear the hub flange of the different types of hub for which the device is designed, and its intermediate portion is formed with a ledge 14 inclined with reference to the body portion of the latch to an extent so that when the latch is swung down behind the flange F of the wheel hub, this ledge will be approximately flush with the inner side of said flange, i. e., transverse of the axial line of the hub. The latch 13 at the locality of engagement with the hub is concaved as indicated at 15, so as to approximately fit the circumference of the hub, so that the latch or stirrup is adapted to fit in closely against the flange F and down to the base thereof as indicated in Fig. 1 when the device is applied for use. The body 10 is also equipped with a hook or beak portion 16 extending from the pivot 100

bore 11 approximately the same distance as the latch 13 and formed with a transverse ledge 17 adapted to be applied to the hub flange F opposite the ledge 14 of the latch and 5 to fit closely in against the hub, being also for this purpose preferably somewhat concaved as indicated at 17a. The beak 16 with its ledge 17 is so designed with reference to the latch 13, that the ledge 17 will lie flush 10 against the hub flange in cooperation with the ledge 14 for a given size of hub, i. e., as shown for the hub of a Ford truck. When 15 the device is to be applied to a smaller hub, e. g., the current type of Ford passenger car, a portion of the hub of which is indicated in Fig. 3 at H', the beak and latch, of course, have to swing in further towards each other, and to effect the proper engagement 20 of the beak with the flange F' of this hub, the beak is provided with a notch or recess 18 in its extremity of a size adapted to receive the flange F' and engage it snugly.

The body 10 is provided with an inward arm or extension 19 approximately at right 25 angles to the beak 16, and this arm is formed with a threaded bore 20 adapted to receive a threaded operating stem or power screw 21. This stem has an extremity 21a adapted to engage the end of the wheel axle A to exert 30 the requisite pressure thereon for extracting the hub therefrom.

These pulling operations ordinarily require that a very considerable turning effort be applied to the power screw and this force 35 places a heavy strain on the puller, and while I have constructed my puller of a configuration most effectively to withstand this strain, it is nevertheless very essential that the device be otherwise such as to reduce 40 this effort and strain to a minimum. It is well known that loosening or pulling operations of this nature are greatly facilitated by jarring or vibrating the object to be loosened. Taking this fact into consideration, I have 45 applied an operating handle 22 to the power screw whereby the screw is not only more easily rotated to effect the pulling operation but where such operation also simultaneously performs the function of vibrating or jarring 50 the puller and hub to assist in loosening the latter from the axle, the handle having an enlarged hub portion preferably integral therewith and rigidly affixed to the outer end of the screw. This handle is provided with 55 one or more hammerheads 23 thereon for receiving the blows of a hammer to cause rotation of the screw, and for convenience I shall herein term such a handle a hammerhead handle.

60 The function and advantages of the hammerhead handle 22 are believed to be obvious. The screw may be rotated by hand to bring its forward end into engagement with the end of the axle. The operator may then continue 65 the rotation of the screw by strik-

ing the heads 23 with a hammer. This method of rotating the screw is not only easier on the operator but serves the additional and more important functions of jarring the puller and wheel and simultaneously giving the screw relatively sudden and sharp turning movements. These simultaneous operations result in loosening the wheel much more efficiently and quickly, as will be understood, and thereby greatly reduces the 75 strain ordinarily placed on pullers of this nature.

It will be noted that by the described construction, and as illustrated, the pressure exerted by the threaded stem 21 is directly intermediate the hub engaging ledges 14, 17 of the latch and beak respectively, so that the operative pressure is always applied directly in line with the hub axis, also that the clamping effect of the latch and beak against 80 the opposite sides of the hub increases progressively as the operative pressure increases, so there is no danger of the device slipping off to injure the hub or puller. By the provision of the supplemental notch seat 18, the 85 device is correctly centered for a range of smaller sizes of hubs as well as for a range of larger sizes.

With the described construction an exceptionally rugged tool is provided with low 90 machining costs and with a capability of being instantly applied to the hub, and as quickly removed therefrom.

I am aware that the invention may be embodied in other forms without departing 100 from the spirit or essential attributes thereof, and I, therefore, desire the present embodiment to be considered in all respects as 105 illustrative and not restrictive, referring to the appended claims rather than to the foregoing description to indicate the scope of the invention.

Having now described my invention, what I claim as new and what I desire to secure by Letters Patent is:

1. A device of the kind described comprising a body equipped with a hub engaging beak, a yoke shaped latch pivoted to said body equipped to engage the hub opposite said beak, said body equipped with an offset extension, and an operating stem threaded in said extension adapted to engage the end of an axle within said hub.

2. A wheel puller comprising a body member equipped with a hub engaging ledge, a member pivoted to said body at a point relatively remote from said ledge and also having a ledge to engage a wheel hub, said body having an offset portion, and an operating stem fitted in said offset portion adapted to engage a wheel axle within such hub, said stem having an operating handle.

3. A wheel puller comprising a body equipped with a hub engaging ledge, said ledge having a notch in the outer portion

- thereof for the purpose stated, a member pivoted to said body equipped with a ledge adapted to cooperate with the ledge on said body for engaging a wheel hub at opposite sides thereof, and an operating stem threaded in said body in relatively offset and transverse relation to said pivot adapted to engage the end of a wheel axle within such hub and to exert pressure in a direct axial line thereof.
- 10 4. A wheel puller comprising a body member, means cooperating therewith to hold the hub of a wheel, a power screw threaded axially into the member for engaging against the end of the axle on which the wheel is mounted, and a hammerhead handle rigidly affixed to the outer portion of the screw for receiving the blows of a hammer to cause rotation of the screw and jarring of the wheel in the pulling operation.
- 15 5. A wheel puller comprising a body member, means cooperating therewith to hold the hub of a wheel, a power screw threaded axially into the member for engaging against the end of the axle on which the wheel is mounted, and a handle rigidly carried by an enlarged hub portion thereof rigidly affixed to the outer portion of the screw and having hammerheads on opposite ends thereof at opposite sides of the screw for receiving the 20 blows of a hammer to cause rotation of the screw and jarring of the wheel in the pulling operation.

In witness whereof I affix my signature this 10th day of June, 1932.

ARTHUR L. CORNWELL.
